EMULSION TREATER

Jay P. Walker, Clarence O. Glasgow, and Alex W. Francis, Jr., Tulsa, Okla., assignors to National Tank Company, Tulsa, Okla., a corporation of Nevada

Application April 11, 1951, Serial No. 220,476

14 Claims. (Cl. 183—2.7)

1

This invention relates to new and useful improvements in emulsion treaters.

One object of the invention is to provide an improved emulsion treater of the horizontal type involving certain features and arrangements which make for more efficient and economical treating.

A particular object of the invention is to provide an improved treater arranged to effectively separate free water, treat the emulsion to efficiently segregate the oil and water components thereof and release the gas therefrom, as well as to scrub such gas so as to delete entrained oil.

A further object of the invention is to provide a heated emulsion treating chamber in the front end of the horizontal tank with a water knockout immediately preceding the treating chamber, whereby the influent stream is denuded of free water just before passing into the treating chamber, in combination with means for diverting the rearward flow of the treated oil, and some water, into the immediate vicinity of the knockout, and flowing the same rearwardly, thereby preventing stagnation of liquids above the knockout and setting up flowing currents through the oil zone, which will be substantially free from gas and undue agitation.

Still another object of the invention is to provide an improved treater wherein substantially all of the gas is evolved at the treating chamber and such gas is carried off in heat exchange relation with the inflowing influent and thereafter scrubbed to remove moisture therefrom.

A construction designed to carry out the invention will be hereinafter described together with other features of the invention.

The invention will be more readily understood from a reading of the specification and by reference to the accompanying drawings, wherein examples of the invention are shown, and wherein:

Fig. 1 is an elevation of an emulsion treater constructed in accordance with the invention.

Fig. 2 is a transverse sectional view taken on the line 2—2 of Fig. 4.

Fig. 3 is a similar view taken on the line 3—3 of Fig. 1.

Fig. 4 is a longitudinal, vertical sectional view of the treater.

Fig. 5 is a longitudinal, vertical sectional view of the volume tank.

Fig. 6 is a front elevation of the treater.

Fig. 7 is a rear elevation of the same, portions of the heat exchanger being in section.

Fig. 8 is a plan view of the treater, and

2

Fig. 9 is a detailed elevation of the rear end portion of the treater from the opposite side to Fig. 1.

In the drawings the numeral 10 designates an elongate cylindrical tank, seated, and supported horizontally, in transverse standards 11, adjacent each end. The lower transverse bottoms of the standards are supported at each side upon longitudinal frame skids 12, connected by cross members 13, welded thereto, whereby a substantial base frame is provided. The standards are suitably fastened on the base frame. A crowned head 14 is secured to the front end of the tank and a similar head 15 is fastened to the rear end of said tank.

A horizontal return-tube heater 16 is inserted through a transversely elongated collar 17 mounted in the head 14, just below the center. As is best shown in Figs. 1, 4, 6 and 8, this collar 20 extends across the head and is flanged whereby a flanged adapter 18 may be secured thereto. This adapter has outwardly extending, transversely spaced, flanged collars 19 and 20. To the right hand collar 19, Fig. 6, a gas burner 21 mounting 22 is secured; the details of this structure being unimportant. A flue-elbow connection 22 is secured to the other or left hand collar 20 (Fig. 6). The burner details are subject to considerable variation and no claim is made thereto.

The heater 16 extends rearwardly in the front end of the tank and has its inner or rear end adjacent an upright, transverse partition 23, having its top spaced below the top of the tank and its bottom well above the bottom of the tank. This partition defines in the front end of the tank, a heating and separating chamber A. A hood or free water compartment B is formed in the medial portion of the tank in rear of the chamber A. The hood is formed by a transverse, top sheet 24 across the tank, having its ends secured to the tank wall, at the central portion.

A transverse, vertical partition 25 is spaced a short distance from the partition 23, forming a flume 26 therebetween, transversely of the tank. The partition 25 has its top edge a short distance below the top sheet and terminates opposite the bottom of the partition 23. From the center of the sheet 24, and at the rear thereof, a cylindrical flume 27 leads through the top of the tank, receiving an influent stream from an exterior horizontal oil and gas separating tank 28. The bottom of the hood is open to the tank and therebelow.

The influent which enters the downcomer pipe or flume 27 flows down into the compartment B, wherein the free water settles out and flows down into the body of water, toward the bottom of the tank. The emulsion accumulates in the compartment and overflows the top edge of the partition 25 into the broad flume 26. Elongate perforated spreaders 29, each triangular in cross-section (Fig. 2) have their forward ends supported on an angular cross bar, under the heater tube 16 at the front end of the chamber A. The bottom of each spreader is open and its rear is secured in the bottom edge of the partition 23, to one side of the center so as to be open to the fluids flowing from the flume 26.

Since more or less sand flows into the compartment B, with the influent stream, and settles downward, where it is accumulated along the bottom of the tank, under the chamber A and compartment B, steam nozzle or jet heads 30 and 31 are disposed relatively between and below the spreaders 29 and under the compartment B, respectively. The heads 30 and 31 are disposed in alignment along with the longitudinal center of the bottom of the tank and each has a longitudinal manifold pipe 32 provided with inwardly and downwardly directed curved jets 33 at each end. Each pipe 32 is supported in clips 34, welded to said bottom. Each head rests in a transverse dam strip 35 at its center, supported upon the bottom of the tank.

Each dam strip extends across a drainage sump 36 in the bottom of the tank, having a flanged outlet 37, adapted to be bolted to a suitable outlet pipe (not shown). Each manifold pipe 32 is equipped, along each side with outwardly directed, downturned jets 33, on each side of each strip 35 and directed toward the same, whereby the sand accumulating along the bottom of the tank is washed into the sumps. Water or gas is supplied to the head 30 by an inlet pipe 39 and its pipe 32 is sealed at each end; while water or gas is supplied to the forward end of the pipe 32 of the head 31 by an inlet pipe 40, the rear end of the pipe 32 being closed (Figs. 4 and 8). The pipes 39 and 40 are bent right-angularly so as to extend through the side wall of the tank and are connected with a suitable source of water or gas supply (not shown).

The sand being precipitated and washed out by the heads 30 and 31 and through the sumps 36, the water being knocked out in the compartment B and commingling with the body of water W, and the influent flowing down the flume 26, as hereinbefore set forth, is spread across this relatively narrow flume and enters the rear open ends of the spreaders 29. The perforations of the spreaders being relatively small, said influent is discharged in numerous and closely spaced, small streams. Since a water level is maintained longitudinally throughout the length of the tank, slightly above the heater 16, forming the zone W, the streams from the perforations are discharged into this body of heated water.

The emulsion streams are discharged from the spreaders 29 (Fig. 2), one under the burner leg 16a and the other under the return leg 16b. These discharged streams flow outwardly and upwardly on the inner and outer sides of the legs, whereby the emulsion is thoroughly heated and the oil, gas and water separated in the usual manner. The oil flows up into the oil zone O to oil level; while the gas escapes into the gas zone G along the top of the tank.

Spaced rearwardly of the partition 23, is an

upright transverse baffle 41, which has its top edge above the oil level in the gas zone and below the top of the tank; while its bottom edge is some distance below the oil level, but above the water level. Theoretically, the oil which passes over the partition 23 and under the baffle 41, will have been dewatered to a large or maximum extent and substantially all of the gas will have been released. The flow rearwardly is largely through the oil zone. An upright perforated partition 42 is mounted transversely in the tank immediately in the rear of the head 31 and spaced rearwardly is a second perforated partition 43. Filtering material 44 is disposed between the partitions and supported on a cross shelf 45, spaced above the bottom of the tank in the water zone. Where tighter emulsions are being handled, the space S below the partition may be filled with filtering material.

The partition 43 is spaced a short distance from the rear head 15 and an outlet compartment F is formed therebetween. In the bottom of the compartment is a steam head 46, constructed along the lines of the heads 30 and 31, and mounted over an outlet 47 having connection with suitable piping (not shown). A water discharge pipe 48 (Figs. 3 and 4) is inclined downwardly from a horizontal outlet pipe 49 extending through a manway 50 to the lower side of a water siphon column 51, closed at its top and bottom. The lower end of the inclined pipe 48 terminates close to the head 46. The pipe 49 is aligned with the water level in the tank, whereby the latter is maintained.

A pressure equalizing pipe 52 leads from the gas zone at the top of the tank, through the tank wall to the upper end of the column 51. An overflow pipe nipple 52' is mounted in the bottom of the column, having its upper end somewhat above the water level in the tank. The body of oil and mixture of oil and water supported on the body of water in the tank will depress the water level therein, so that the water in the column 51 will rise much higher than in the tank. A discharge pipe 53 (Figs. 3, 7 and 9) leads from the bottom of the nipple 52' and is directed horizontally to a water valve 54, which has a suitable outlet pipe connection 55.

The well emulsion is conducted by a pipe 56 to one end of the lower leg of a heat exchanger 57 (Figs. 1, 4 and 7). The upper and lower legs of the exchanger are of standard construction and are supported across the rear end of the tank, exteriorly thereof. The emulsion flows through tubes 58 (Fig. 7) to a chamber 59 at the opposite end of the leg from which it escapes through a pipe 61 to the chamber 62 of the upper leg. From the chamber 62 the emulsion passes back through tubes 63 to a chamber 64 at the opposite end of the upper leg and is discharged through a nipple 65 into an angular pipe 66 (Figs. 1, 7 and 8). The angular pipe 66 leads to and discharges into the side of the horizontal exterior tank 28.

The dewatered and degassed or clean oil, from the zone O, overflows into the outlet box 67, at the oil level in the compartment F. The oil filling this box escapes through an angular outlet pipe 68, which enters the top of a volume tank 69 (Figs. 4, 5 and 7). This tank is mounted transversely above the heat exchanger 57 and is supported thereon at one end by a bracket 70, carried at one end of the upper leg of the heat exchanger; while at its opposite end the volume tank is supported by and connected with, the upper leg of the exchanger 57 by an outlet pipe

It connected with the heat exchange section of the lower leg by a pipe 14. The cooled oil escapes from the exchanger through an outlet pipe 12 (Figs. 1, 7 and 8). This outlet pipe 12 has a diaphragm outlet valve 13 (Figs. 7, 8 and 9) connected therein.

In the volume tank 28 a float 15 is mounted on the end of an arm 16 mounted on a rock shaft 17 (Fig. 5) which is housed in a bonnet 18. A lever arm 19 (Figs. 7 and 8) is hinged on the rock shaft 17 and connected with valve arm 89 of a control valve 81. A gas line 82 leads from the tank 28 and is bent at right angles so as to extend down to the base of the tank (Fig. 9), where it is connected to a horizontal pipe 83 connected with a diaphragm valve 84, having a suitable disposal connection.

A gas supply elbow 84 (Fig. 9) is mounted on the side of the gas pipe 82 and a gas supply line 85 is connected thereto. This line leads to and connects with the valve 84 and with the bowl of a diaphragm pressure responsive member 89. The member 89 is mounted on a steam pipe 88 mounted on the water outlet pipe 53 and controls the water outlet valve 54. The valve 54 has the usual lifting arm 91 linked to a weighted lever arm 92 mounted on and controlled by the diaphragm member 89. A gas supply line 86 leads from the valve 81 to the lower bowl of the diaphragm 73 of the oil valve 12, and a second gas supply line 87 leads from the line 86 to the upper bowl of the diaphragm of the gas valve 84.

The influent stream from the heat exchanger 57 (Figs. 1, 6 and 7) which is conducted by the pipe 66, is discharged into a jacket or shell 93, disposed axially in the gas separator tank 28. This shell (Figs. 4 and 7) is mounted toward the front end of the tank, has its inner end closed and is provided with a cross partition 94, whereby a box 95 is formed at the inner or rear end of said shell. The influent oil pipe 66 discharges into the shell in front of the partition (Fig. 7). A gas discharge pipe 96 leads from the top of the tank 28 and is bent and directed axially through the shell and the partition 94, so as to discharge into the box 95 which has outlets 97, whereby the gas may escape into the tank 28 around the shell.

The oil which enters the rear end portion of the shell 93 flows forwardly therein, around the gas pipe 96, in heat exchange relation with the gas flowing rearwardly in said pipe. This emulsified oil stream from the shell discharges into the tank 28 and exits by way of the pipe 27. The gas which is discharged into the separator tank 28 passes rearwardly between the inclined scrubbed plates 98 to the rear of said tank where it escapes by way of the pipe 82.

In operation the influent from the well is conducted by the pipe 55 (Figs. 1, 4, 7 and 8) to the lower leg of the heat exchanger 57 and flows through the tubes 58 to the chamber 59 at the right hand (Fig. 7) end. The influent passes up through the pipe 61 to the chamber 62 of the upper leg, thence through the tubes 63, back to the chamber 64 (Fig. 7) from which it escapes through the nipple 65. As will be hereinafter pointed out, the incoming influent flows in heat exchange relation with the outflowing warm clean oil and is thereby heated or warmed.

The influent flows up the pipe 66 and then horizontally (Figs. 1 and 8) and enters the tank 28, through the side thereof to the shell 93, into which it discharges (Figs. 4 and 7) in front of the partition 94. The influent then flows forwardly in the shell and being cooler than the hot gases

flowing rearwardly, through the pipe 96, will cause condensation of any heavy hydrocarbons in the gas stream. The influent flow discharging from the front end of the shell, accumulates on the bottom of the tank 28 and discharges down into the downcomer pipe 27 into the free water compartment B. In this compartment, the free water settles out of the influent and flows along the bottom of the tank 28, commingling with the body of water maintained therein.

In order to assure the settling out of substantially all free water, the upright partition 25 (Fig. 4) is employed. Since the top edge of said partition is quite close to the top sheet 24 (usually about 2 inches) only emulsion from immediately under said sheet escapes into the flume 26. This will give the free water flowing into the chamber B, a full opportunity to settle out. The downflowing influent emulsion, which has been de-watered, upon reaching the bottom of the flume, will flow into the rear ends of the two perforated spreaders 29 (Figs. 2 and 4) and forwardly therein.

It might be well at this stage to point out the disposition of the sand. In some influents large quantities of sand are suspended in the influent and are carried thereby. By reason of the retardation and settling afforded in the compartment B, sand will drop out and spread along the bottom of the tank under the nozzles 30 and 31. Water or gas being ejected by the jets 33 and 38, the sand will be impelled toward and into the sumps 36, from which it is periodically withdrawn.

Since the partition 25 terminates on a level with the bottoms of the triangular spreaders 29, entry of the influent into the spreaders, is assured. The influent flowing forwardly in the spreaders is discharged in upwardly flowing, closely spaced, small streams which impinge the bottoms of the burner legs 16a and 16b (Fig. 2), longitudinally thereof so as to flow upwardly around each side of each leg in the body of water W. This thorough heating, not only maintains a warm body of water W around the heater, but causes the emulsified constituent to break down, whereby the oil and water are separated, the water tending to settle and the oil rising.

Where gas is in solution with the emulsion, it will be released when the emulsion is broken around the heater and as the oil and oil-gas globules flow upwardly into the oil zone O. The oil level is controlled by an outlet box 67 at the rear end of the tank. Gas rises from the oil into the gas zone G along the top of the tank. It will be noted that the partition 23 and baffle 41 are so disposed as to cause the oil, in its rearward movement toward the outlet box 67, to flow over the top of the partition and down under the lower edge of the baffle 41, just above the water level. Substantially all of the gas is evolved in this area.

By causing the rearwardly flowing oil in the zone O to take downward path between the partition 23 and baffle 41 and under the latter, the effect is to reduce the temperature of such oil, one or more, up to several degrees, Fahrenheit. Due to this cooling no warm gas will evolve and thus the entire horizontal surface and body of oil, in rear of baffle 41, is not agitated and settling is most efficient, because substantially no gas is breaking out of the liquids. The oil which flows rearwardly and the upper strata of the water in zone W, pass through the upright, transverse filtering material 44, above the shelf 45. If

needed, the space below the shelf can be filled with filtering material. The filtered oil and water stratify in the outlet compartment F.

As some sand may precipitate in the compartment F, arrangement is made to drive it out by means of a water or gas head 46, and an outlet 47. A water level is maintained in the tank by the means shown in Figs. 3 and 4. The inclined pipe leg 48 carries water up and out through the pipe 49 into the lower end of the water siphon column 51, from which it escapes into the nipple 52 and thence out through the pipe 53 to the water valve 54 (Fig. 9).

The warm clean oil which overflows into the box 67 is carried out through a pipe 68 (Figs. 4, 5 and 7) to the volume tank 69 from which it escapes down through the pipe 71. An oil level is carried in this tank by means of the float 75 (Fig. 5) which controls the gas supply through the elements 81 and 86 to the diaphragm 73 of valve 72. The gas supply to the gas outlet valve 84 is also controlled by the valve 81. The warm oil escaping through the pipe 71 (Fig. 7) flows into the upper leg of the heat exchanger 57 and around the tubes 63 therein, escaping from the bottom through a pipe 74 into the top of the lower leg around the tubes 58, thereof and finally escaping through the valve 72.

The gas escaping from the zone G by way of the pipe 96 flows through the shell 93 and discharges into the box 95. Some cooling may take place in the pipe 96 within the shell, and these heavier hydrocarbon condensates will escape through the lower opening 97 into the tank and flow to the pipe 27. The gaseous fluids will flow between the inclined scrubber plates and escape by way of the pipe 82.

It is pointed out that the partition 23 and baffle 41 directing the flow downwardly, prevent a layer of stagnant oil overlying the top sheet 24 of the water knock-out B. This flow of oil causes sufficient agitation through the oil zone to maintain the grade of oil. Since all the separable gas evolves at the heater and the oil being immediately cooled by flowing adjacent the top of the water knock-out, substantially no more gas is evolved, during the rearward travel of the oil and consequently there is no more agitation.

The foregoing description of the invention is explanatory thereof and various changes in the size, shape and materials, as well as in the details of the illustrated construction may be made, within the scope of the appended claims, without departing from the spirit of the invention.

What we claim and desire to secure by Letters Patent is:

1. An emulsion treater including, an elongate horizontal treating tank having a front end and a rear end, a treating chamber in the front end of the treating tank, a return-tube heater disposed longitudinally in the front portion of the tank, a transverse upright partition across the tank immediately in rear of the heater, water and oil zones longitudinally in the tank from one end to the other end thereof, said partition having its lower end in the water zone above the bottom of the treating tank and its upper end in the oil zone, a pair of spreaders having inlets at the bottom of the partition and extending forwardly under the heater, a water-knock-out hood contiguous to the partition having its bottom open in the water zone above the bottom of the tank, an influent inlet leading into the tank to the top of the hood, and oil and water outlets from the tank.

2. An emulsion treater as set forth in claim 1, with a transverse flume in the hood having a narrow transverse inlet at its top and discharging into the spreaders at its bottom.

3. An emulsion treater including, an elongate horizontal treating tank having a front end and a rear end, a treating chamber in the front end of the treating tank, a return-tube heater disposed longitudinally in the front portion of the tank, a water knock-out hood adjacent the heater in the tank, spreaders extending from the hood under the heater, an influent conductor connected with the hood, a gas outlet in the top of the tank, an oil outlet in the rear end of the tank at the oil level, a water outlet at the rear end of the tank, an exterior volume tank at the rear end of the treating tank having a float therein, a heat exchanger, an oil outlet from the volume tank to the heat exchanger, an oil outlet valve connected with the heat exchanger having a diaphragm operator, a gas line connecting the gas zone of the treating tank with the diaphragm operator including a valve and connected with the tank float, an influent inlet to the heat exchanger, and an influent conductor leading from the heat exchanger and having connection with the influent conductor connected with the hood.

4. An emulsion treater as set forth in claim 3 with an oil and gas separating tank connected with the influent conductors and having a gas inlet from the treating tank and a gas outlet.

5. An emulsion treater including, an elongate horizontal treating tank having a front end and a rear end, a heating chamber in the front end of the tank having a heater therein and an influent spreader below the heater having an entrance at its rear end, a water knockout compartment in the tank intermediate the ends thereof and having an open bottom spaced at its rear edge from the bottom of the tank whereby fluid may escape into the tank from the rear edge of the compartment, the spreader being connected to the front edge of the compartment whereby fluid normally escapes from the compartment to said spreader, an influent conductor leading to the knock-out chamber, and gas, water and oil outlets from the tank.

6. An emulsion treater as set forth in claim 5, a plurality of nozzles under the spreader and the knock-out compartment, means for supplying a flushing fluid to said nozzles, and sediment outlets from the bottom of the tank adjacent said nozzles.

7. An emulsion treater including, an elongate horizontal tank having a front end and a rear end, a treating chamber in the front end of the tank having heating means therein and an influent spreader below the heating means having an entrance at its rearward end, a water knockout compartment immediately in rear of the chamber and having a wall in common with the chamber, the knockout compartment having an outlet directly to the spreader, an influent conductor leading through the tank to the knockout compartment, an elongate horizontal stratifying chamber extending from the treating chamber over the knockout compartment to the rear end of the tank providing an elongate horizontal flow path and separating zone with large liquid surfaces whereby full stratification and separation of the oil and water and gas are enhanced, an oil outlet in the rear end of the tank maintaining an oil level in the tank, a gas outlet from the tank above the oil level therein, and

a water outlet from the tank maintaining a water level therein, whereby oil and water and gas zones are provided in the tank, the tank having an open continuous space extending along its bottom wall from beneath the treating chamber through the bottom of the stratification chamber and passing beneath the knockout compartment, the bottom of the knockout compartment opening into said space, whereby an elongate continuous water accumulation and flow space is provided in the bottom of the tank.

8. An emulsion treater as set forth in claim 7 wherein the wall common to the treating chamber and the knockout compartment is formed by an upright partition having its upper edge adjacent and below the oil level.

9. An emulsion treater as set forth in claim 8, and a transverse upright baffle in the tank over the knockout compartment and spaced rearwardly from the partition, the baffle extending from above the oil level to a point spaced above the top of the knockout compartment whereby heated liquids flowing from the treating chamber must pass downwardly and under the baffle in close proximity to the top of the knockout compartment.

10. An emulsion treater as set forth in claim 7, with a vertical flume leading from the top portion of the knockout compartment to the entrance of the spreader.

11. An emulsion treater as set forth in claim 7, with an oil and gas separating tank exterior of the treating tank, a gas conductor leading from the gas outlet of the treating tank into the separating tank, an influent pipe leading into the separating tank, a conductor in the separating tank connected to the influent inlet pipe and in heat exchange relation with the gas conductor, and an outlet from the separating tank connected with the influent conductor of the treating tank.

12. An emulsion treater as set forth in claim 7, with an oil and gas separating tank exterior of the treating tank, a gas conductor leading from the gas outlet of the treating tank into the separating tank, an influent pipe leading into the separating tank, a conductor in the separating tank connected to the influent inlet pipe and in heat exchange relation with the gas conductor, an outlet from the separating tank connected with the influent conductor of the treating tank, a scrubber in the separator tank disposed beyond the gas conductor, and a gas outlet pipe leading from the separating tank beyond the scrubber.

13. An emulsion treater as set forth in claim 7

wherein the oil outlet includes an oil discharge conductor leading from the tank, and a volume tank into which the oil discharge conductor is connected, a float in the volume tank and an oil drain valve connected to the volume tank and having an actuating connection with the float.

14. In an emulsion treater, an elongated horizontal treating tank having a front end and a rear end, a treating chamber in the front end of the tank having a heater therein and an influent spreader below the heater having an entrance at its rear end, a water knockout compartment immediately in rear of the chamber having an outlet directly to the spreader, an influent conductor leading through the tank to the compartment, an elongate horizontal stratifying chamber extending from the treating chamber over the knockout compartment to the rear end of the tank providing an elongate horizontal flow path and separating zone with large liquid surfaces whereby full stratification and separation of the oil and water and gas is enhanced, an oil outlet in the rear end of the tank maintaining an oil level in the tank above the compartment, a gas outlet from the tank above the oil level therein, a water outlet from the tank maintaining a water level therein, whereby oil and gas zones are provided in the treating tank, a filter in the tank contiguous to the oil outlet and extending downwardly through the oil level, a pair of spaced vertical foraminous partitions in the stratifying chamber adjacent the oil outlet, said partitions extending substantially from the bottom of the tank to the top thereof, and a filter support between the latter partitions below the water level, the filter being disposed between the partitions and in at least the space above the support.
